(57) CLAIM

I claim the ornamental design for a bottle, as shown and described.

DESCRIPTION

FIG. 1 is a perspective view of a bottle in accordance with the present invention.

FIG. 2 is a side view thereof, the other side views being equivalent.

FIG. 3 is a top view thereof; and,

FIG. 4 is a bottom view thereof.

The broken lines show a portion of the bottle that forms no part of the claimed design.
